UNITED STATES PATENT OFFICE.

EDWARD J. MAYER, OF HAMMOND, INDIANA.

CARBOY HOOD.

Application filed August 28, 1919. Serial No. 320,493.

To all whom it may concern:

Be it known that I, EDWARD J. MAYER, a citizen of the United States, residing at Hammond, in the county of Lake and State of Indiana, have invented certain new and useful Improvements in Carboy Hoods, of which the following is a specification.

My invention relates to hoods for protecting the carboys or bottles while in route.

10 One of the objects of the invention is to provide a replaceable hood or cap with a means secured to the carboy casing whereby the hood may be placed over the exposed or protruding neck of the carboy, where it projects from the upper wall of the casing containing the carboy, and conveniently removed thereon and used indefinitely for the purpose.

15 It is the usual practice to place on a casing, containing a carboy for destructive acids, a temporary structure consisting of two pieces of boards with their upper ends secured together and their lower diverging ends nailed to the top wall of the casing on 20 each side of the protruding neck of the enclosed carboy. These structures are usually destroyed upon receipt of the package, so that every time a casing containing an acid laden carboy is shipped, a new neck-protecting hood must be furnished.

25 My invention is concerned with a type of hood that may quickly be secured in place and as quickly and easily removed without requiring any extraneous attaching means.

30 It further contemplates a hood that may be used over and over again, thereby saving the expense of furnishing a new hood each time a carboy is shipped.

35 It further has to do with the provision of a safer protecting means and one so easily of application that it may be taken off and replaced each time a part of the contents is taken from the carboy.

40 Other, further and more particular objects of my invention will become readily apparent to persons skilled in the art, from a consideration of the following description when taken in conjunction with the drawings, wherein:—

45 Fig. 1 shows a fragment of the casing and an elevation of my improved device detachably connected thereto.

50 Fig. 2 is an enlarged section taken on line 2—2 of Fig. 1.

Fig. 3 is a vertical section taken on line 55 3—3 of Fig. 2.

Fig. 4 shows a detail of the structure exemplified in the foregoing figures, it being a part of a bayonet joint by which the hood is attached to the casing.

Fig. 5 is an elevation of a modification of the device, or another form which it may take.

Fig. 6 is an enlarged section taken on line 6—6 of Fig. 5.

Fig. 7 is a section taken on line 7—7 of Fig. 6.

Fig. 8 is an elevation in perspective of the removable portion of the cap-protecting device.

Fig. 9 shows the means of joining the two members of the angular portions of the device shown in Fig. 8.

55 In all the views the same reference characters are employed to indicate similar parts.

The preferred form of the device consists of a dome-shaped hood 10 pressed out, preferably, from sheet metal and to give it strength it is corrugated, as at 11. A 60 flange 12, to which the hood is detachably connected, is secured to the wall 13 of the carboy casing by lag screws 14. The casing wall 13 is perforated for the neck 15 of the carboy 16. The structure 12 is provided with a vertical rim 17 having on 65 opposite sides a groove 18 which serves as a member for a bayonet joint by which the hood 10 is attached. Near the lower end of the hood are detents 19 that are adapted to fit in the grooves 18 of the flange 17 so that it may readily be seen that it is only necessary to turn the hood 10 part of a revolution until the detents 19 come to the end of the slots 18 when it may be raised 70 out thru the slots 20, thereby removing the hood from over the neck 15 of the carboy. A closure 21, such as suitable cork, stopper, or the like, is secured in the mouth of the neck 15 to prevent spilling of the 75 contents.

80 In Figs. 5 to 9 inclusive I have shown a modified form in which the hood 10' consists of a single piece of metal, bent as at 22, and having two walls 23 and 24, diverging from the apex, each having a base part 85 25. The walls have at their edges on either side, tongues 26 and 27, that slidably en-

2
gage each other, the projecting portion 28 of tongue 26 entering a slot 29 of the tongue 27 so that the members 23 and 24 may be moved toward and from each other, and 5 whereby the neck 15 may be protected on all sides by enclosing walls. A base plate 30 is secured to the walls by means of bolts, or otherwise, and at each of its ends is provided with a groove 31 overlain by a flange 32 within which the base portion 25 of the member 10' enters. When it is desired to remove the hood 10' from its position on the carboy casing, the two members 23 and 24 are pressed toward each other so 10 that the base parts 25, or either of them, slips out of the groove 31 whereupon raising the end of the member 10' that has been removed from under the flange 32, the device may readily be removed from its position over the neck 15 of the carboy. The 15 natural resiliency of the metal, composing the structure 10' is sufficient to hold the base portions 25 in their respective grooves. In either of the structures illustrated in the 20 drawings, the hood may be easily and quickly removed from its protecting position and just as quickly and easily replaced and, after it has been initially provided, it 25 may be used from time to time to perform its intended function.

While I have herein shown a single embodiment of my invention, and one modification thereof, for the purpose of clear disclosure and for showing a relatively broad aspect of the invention, it will be manifest 30 to persons skilled in the art, that it is susceptible of other modifications and other

changes in the configuration and relation of the parts within the scope of the appended claims.

Having described my invention, what I claim is:—

1. A detachable hood for a carboy, having a separable flange for permanent association with the carboy and an integral hood 45 comprising a closed dome-like cover, said cover providing inwardly projecting integral parts forming attaching members with slots in the flange, the rounded closed end of the hood being substantially smooth and 50 the opening in the hood, surrounded by a substantially smooth band, the cylindrical part of the hood between the dome and band being corrugated.

2. In combination with a carboy casing, 55 or wooden box, through which the neck of the carboy extends; a flange of relatively thick metal having adjoining circumferentially and downwardly extending grooves 60 and vertical connecting grooves in its outer vertical surface to provide hood fastening members and surrounding the neck of the carboy and extending nearly to the top thereof to protect the neck from danger of fracture; a closed hood having a spherical 65 top and an open bottom end to surround the flange and indented projections extending inwardly from the hood into said grooves to hold the hood in place and means 70 to secure the structure to the casing or box.

In testimony whereof I hereunto subscribe my name.

EDWARD J. MAYER.
